UNITED STATES PATENT OFFICE.

ARTHUR J. VERVAET, OF NORTH HALEDON, NEW JERSEY.

LOOM-SHUTTLE MOTION.

Application filed June 4, 1927. Serial No. 196,499.

This invention relates to looms and particularly to the means for impelling the shuttles through the warp sheds. The principal object is to provide for the driving of the shuttle through the shed by force acting thereon, not by a blow or impact characterizing the shuttle driving in ordinary broadware looms, but by force operating practically continuously throughout the flight of the shuttle, as

10 in ordinary narrowware looms. But, instead of the shuttle actuators being arranged only on each side of the weaving space so as to be bridged by the shuttle (as suitably rotated pinions engaging rack-teeth on the shuttle, as 15 in such narrow-ware looms), the shuttle actuators in accordance with my object are arranged and effective on the shuttle within the lateral bounds as well as laterally of the weaving space, whereby the width of the 20 goods will not be limited by the necessity of providing a space sufficiently narrow for the shuttle to span. In short, my object is to provide for a continuously acting shuttle drive in the use of which there need be no 25 limitation to the width of the goods in practice, such as there is in the ordinary narrow-ware shuttle drive.

In the accompanying drawings,

Fig. 1 is a side elevation of a loom embodying the improved shuttle drive;

Fig. 2 is a front elevation of the upper part of the batten-including structure of a loom constructed to embody my invention;

Fig. 3 is a front elevation of a fragment of what Fig. 2 shows, on a larger scale and partly in section;

Fig. 4 is a sectional view, on substantially the line 4—4 of Fig. 3, on a still larger scale;

40 Figs. 5 and 6 are front and end elevations of what is shown in Fig. 2, with the shuttle and cam slides removed;

Fig. 7 is an enlarged sectional detail illustrating how each cam slide may be connected to the means for reciprocating the same;

45 Figs. 8 and 9 are sectional views on the lines 8—8 and 9—9 of Fig. 1; and

Figs. 10 and 11 are top and front elevations of a modified form of the invention.

1 is a loom frame, 2 a suitably driven shaft 50 journaled in the frame below and adapted to drive the crank shaft 3, also journaled in the frame, through gearing 4—5 having a 2—1 ratio, substantially as shown. The batten-including structure is connected with the cranks on the crank shaft 3 in the usual way by pitmen 6 and it comprises the lay-swords

7, mounted on the fulcrum or rock-shaft 8 journaled in the frame 1, and two horizontal rails 9 arranged one above the other and suitably secured to the upper ends of the lay-swords.

Each of these rails 9 is bored for practically its full length with a row of vertical holes, the row of holes in one rail being in the same vertical plane as the row of holes in the other rail. Each hole is occupied by a bushing 10 which receives a pin 11 having at one end a roller 11^a and its other end 11^b flattened. The ends 11^b in the two rows adjoin each other. The rollers 11^a of the several pins 70 lie in the same vertical plane, the pins being kept against rotation by opposite studs 12 which project through vertical slots 10^a in the bushings into spring housings 13 containing springs 14 which act to hold the pins in 75 the two rows pressed apart. Said pins form the mentioned actuators.

The shuttle 15 has a longitudinal groove 15^a in each of its top and bottom surfaces, such grooves being adapted to receive the flattened ends of its rows of actuators (see Figs. 3 and 4); each such surface is at each end of the shuttle inclined with respect to its path of travel, being in the present example beveled toward the end of the shuttle. Therefore if any two opposite actuators (one from each row) are forced together against the oblique or beveled portions 16 at either end of the shuttle at that time intervening they will act to cam the shuttle along its path of travel. 85 By continuing this operation progressively throughout the actuators in each row, first in one direction and then in the other, the shuttle will be caused to reciprocate back and forth; in fact, treating either row as a guide or race 90 for the shuttle the same result would follow if the other row of actuators were thus operated. Since the flattened ends of the actuators engage in the shuttle grooves 15^a the shuttle is kept from riding or wiping upon 100 and otherwise out of contact with the warp shed which, as it opens, is penetrated by the actuators at top and bottom.

The actuators in each row are successively moved toward the shuttle by a reciprocated 105 system including slides having cams. In the present case there are two such slides, individually guided to move but moving together in paths parallel with that of the shuttle. These and their guiding means are reverse 110 counter-parts of each other, so a description of one will serve for the other: Each cam

slide 17 has a pair of spaced cams 18 which are opposed to the roller-equipped ends of the actuators and whose cam surfaces 18^a are substantially parallel with the corresponding oblique surfaces 16 of the shuttle and spaced about as far apart as the latter, though preferably a trifle further apart. Each cam slide is equipped with rollers 19 which run on tracks 20^a formed on channel-strips 20 projecting from the rail 9 with their channels facing each other. The channels of each two channel-strips receive the upper and lower stretches of an endless chain 21 which extends around sprocket-wheels 22 journaled one at each end of the rail 9 and has its pintles 21^a guided in grooves 20^b in the channel strips. Each slide is connected to the upper stretch of the corresponding chain by having a stud 23, projecting upwardly from a projection 17^a on the cam slide, extending between two links in the chain (Fig. 7). The chains must of course move in the same (rotary) direction and together, and for this purpose the sprocket-wheels 22 at one end of the batten structure have bevel pinions 24 which are in mesh with bevel pinions 25 on a vertical shaft 26 journaled in the batten structure. This shaft 26 is driven, through suitably inter-gearred shafts 27 and 28 journaled in the batten-structure all as best shown in Figs. 1, 5 and 6, from a bevel gear 29 which is fixed on a revoluble sleeve 30, journaled in the frame 1 concentric with the fulcrum shaft 8 of the lay-swords (Fig. 9). Sleeve 30 has affixed to it a pinion 31 with which engage the teeth of a rack 32 projecting rearwardly and connected to and supported at its rear end by a depending lever 33 fulcrumed on a vertically adjustable stud 34 carried by a bracket 35 attached to frame 1; a guide roller 32^a maintains the rack in engagement with pinion 31. The upper end of lever 33 has a slot 33^a receiving a pin 36^a on a slide-bar 36 which has a pair of depending spaced jaws 37 between which is arranged a stud 38 on gear 4. The space between the jaws 37 is greater than the diameter of the stud so that between shifting of the slide-bar, and hence of the rack, first in one direction and then in the other, there is a dwell. Hence, in view of the 2-1 ratio of the gear 4-5, the cam slides 17 and hence the shuttle during each half-rotation of gear 4 will shift in one direction, the shed being then open and the batten structure back, and then come to a dwell while the shed changes and the reed (not shown) beats up.

In that form of the invention above described, while the relatively rearward cam face 18^a of each cam slide is operative to advance the shuttle by displacing the actuators against its rear cam-faces the other or leading cam acts also, i. e. to displace the actuators into the path of the shuttle so as to prevent it running ahead and so keep it in control. But, by the modification shown in Figs.

10 and 11 the cams are movable and so controlled that those cams which are leading in either direction are withdrawn from active position. Each slide 39 in this case has sockets 39^a in which the stems 40^a of the forwardly and backwardly sliding cams 40 are guided. The stems of these cams have pins 40^b with which engage forks 41^a on a lever 41 fulcrumed to move in a horizontal plane on the slide. This lever is movable back and forth, by engagement of a lug 41^b thereon with one or the other of fixed detents 42 (only one being shown) projecting from channel strips 20, thus to shift one cam into and the other out of operative relation to the row of actuators, 43 being a click-pawl to hold the lever at each limit of its movement until it is again moved. When the lever shifts in either direction and is then shifted by contact of its lug with a detent at the end of the stroke, the previously active cam is withdrawn and the other operatively positioned preparatory to the return stroke. In Figs. 10 and 11 this change has just been effected on completion of a stroke of the slides to the right. In these Figs. 10 and 11 the other parts are the same as in Figs. 1 to 9.

Since the shuttle is beveled at both ends springs or other means for normally holding the actuators retracted are not indispensable, though the presence of such means is desirable to eliminate the resistance they would otherwise oppose to the shuttle.

By the term "end-surface" in the claims I mean a surface so positioned that the camming action effects displacement of the shuttle lengthwise as distinguished from transversely of the race.

Having thus fully described my invention, what I claim is:

1. In combination, means affording a shuttle race, shuttle driving means extending lengthwise of and spaced from the race and including longitudinally arranged shuttle-driving portions individually movable toward the race, and having their ranges of movement wholly at one side of the same, means to hold the warp stretched in a plane extending between the first two means, a shuttle movable along the race and having an end-surface against which said portions are active cam-fashion, and means to successively urge said portions against said end-surface to advance the shuttle along the race.

2. In combination, means affording a shuttle race, shuttle driving means extending lengthwise of and spaced from the race and including longitudinally arranged shuttle-driving portions individually movable toward the race, and having their ranges of movement wholly at one side of the same, means to hold the warp stretched in a plane extending between the first two means, a shuttle movable along the race and having relatively oppositely facing end-surfaces

against which said portions are active cam-fashion, and means to successively urge said portions against said end-surfaces in alternation to advance the shuttle first in one and 5 then in the other direction along the race.

3. In combination, opposed substantially parallel and spaced shuttle-driving means affording between them a path for the shuttle and each including longitudinally arranged 10 shuttle-driving portions individually movable toward said path, and having their ranges of movement wholly at one side of the same, means to hold the warp stretched in a plane extending between said opposed driving 15 means, a shuttle guided between said means for movement along said path and having end-surfaces against which said portions of both means are respectively active cam-fashion, and means to successively urge 20 said portions of both means against the respective end-surfaces to advance the shuttle along said path.

4. In combination, means affording a shuttle race, shuttle driving means extending lengthwise of and spaced from the race and including longitudinally arranged shuttle-driving 25 portions individually movable toward the race and having their ranges of movement wholly at one side of the same, and spaced from each 30 other and formed with free ends adapted on such movement to penetrate a warp-shed, means to hold the warp stretched in a plane extending between the first two means, a shuttle movable along the race and having an

end-surface against which said portions are 35 active cam-fashion, and means to successively urge said portions against said end-surface to advance the shuttle along the race.

5. In combination, means affording a shuttle race, a shuttle arranged to travel along the 40 race and having an inclined end-surface, actuators arranged in a series opposite to and extending longitudinally of the race and individually movable toward the race and against said incline, and having their ranges 45 of movement wholly at one side of said race, means to hold the warp stretched in a plane extending between the first two means, and means to successively urge the actuators against said end-surface to advance the shuttle 50 along the race.

6. In combination, a frame, a back-and-forth-moving batten-including structure therein having means to guide a shuttle through the warp-shed, a shuttle guided by 55 said means, a reciprocating slide, means to transmit reciprocating motion from the slide to the shuttle, rotary members intergeared to rotate at a speed ratio of 2 to 1, means to transmit reciprocation from the rotary member 60 rotating at the faster speed to said structure, the other rotary member having an eccentric stud, a slide-bar movable in the frame and having a recess receiving the stud, and power-transmitting mechanism connecting 65 the slide-bar and slide.

In testimony whereof I affix my signature.

ARTHUR J. VERVAET.
